UNITED STATES PATENT OFFICE

2,403,065

LATCH

Harry Engert, Chicago, Ill.

Application November 15, 1943, Serial No. 519,327

4 Claims. (Cl. 292—57)

1

My invention relates to latches. One of the objects of my invention is to provide an improved latch having a loop handle portion which will gravitate to blocked position in either the latched or unlatched condition.

A further object is to provide such a latch construction which can be inverted so that the latch bolt can be made to project either to the right or to the left as desired.

A further object of my invention is to provide an improved U-shaped keeper which can be used in either one of two positions with respect to the bolt.

Further objects will appear from the description and claims.

In the drawing in which an embodiment of my invention is illustrated:

Figure 1 is a front elevation of a latch construction showing the bolt projecting toward the right;

Fig. 2 is a plan view of the construction shown in Fig. 1;

Fig. 3 is a section of the line 3—3 of Fig. 1;

Fig. 4 is an elevation showing the bolt supporting bracket inverted and the bolt projecting toward the left and showing the keeper turned 90 degrees from the position shown in Fig. 1; and

Fig. 5 is a plan view of the construction shown in Fig. 4.

The construction shown in the drawing comprises a latch 1 shown as secured to a swinging door 2 and a keeper 3 shown as secured to a door frame 4. The latch shown comprises a bolt supporting bracket 5 and a latch bolt 6 slidably mounted therein. The bracket may be formed of sheet metal comprising a base 7 to be secured to the door by means of screws 8 and a pair of ears 9 extending forwardly from the base having aligned apertures in which the bolt 6 slides and in which it may swing about the axis of the bolt for swinging the bolt from blocked to non-blocked position. The bolt may be formed of an integral rod bent to provide a loop handle portion 10 swingable and slidable with the bolt, the sides 11 and 12 of which loop straddle one of said ears 9 and the side 12 of which is straddled by the ears 9.

The bracket is provided with abutment or blocking means 13 located in the path of sliding movement of the straddled side 12 of the loop when the loop is in depending position as shown in Figs. 1 and 4 and located out of the path of sliding movement of this side of the loop when the loop is swung to substantially horizontal position as shown in Fig. 3. The abutment means

2

13 shown comprises a U-shaped strap secured in any suitable manner as by spot-welding or the like to the base of the bracket. The side 12 of the loop can slide between the arms 14 of the 5 U-shaped strap when the loop is swung to horizontal position as shown in Fig. 3, thus enabling the side 12 of the loop to slip from one side to the other of the abutment means.

When the loop is in the position shown in full 10 lines of Fig. 1, the end 15 of the latch bolt is engaged underneath the U-shaped portion of the keeper 3 to hold the bolt in latching position. To release the latch, the loop will have to be swung to horizontal position as shown in Fig. 3 and then 15 slipped to the left as viewed in Fig. 1 to release the bolt from the keeper. The loop is then allowed to drop down to the dotted-line position shown in which the latch bolt 6 will be blocked by the abutment 13 in nonlatched position.

20 As shown in Figs. 1 and 4, the latching movement of the latch bolt 6 is limited by the engagement of the end portion of the side 12 with one of the ears 9.

The keeper 3 shown may be secured to the 25 door frame either as shown in Figs. 1 and 2 for one type of door construction, or in the position shown in Figs. 4 and 5 for another type of door construction. This keeper comprises a strap shaped to provide a U-shaped bolt engaging portion 16 and securing flat foot portions 17 extending laterally from the legs of the U-shaped portion and provided with openings for the reception of the securing screws 18. The connecting portion 19 of the U-shaped portion is offset with 30 respect to the plane of the foot portions 17 to enable the bolt to slide underneath the connecting portion when the keeper is positioned as shown in Figs. 1 or 2, with the plane of the foot portions parallel to the axis of the latch bolt. The connecting portion 19 has a bolt receiving opening 20 therethrough to receive the end 15 of the latch bolt when the keeper is positioned so that the 35 plane of the flat foot portions 17 is transverse to the axis of the bolt as shown in Figs. 4 and 5.

If desired, the shape of the U-shaped abutment member 13 may be the same as the shape of the U-shaped portion 16 of the keeper. This enables the abutment member to be formed using the 40 same dies as are used in forming the keeper member. The keeper and the latch bracket may both be formed of stamped sheet metal.

It is intended, of course, that the invention 45 should not be limited to the specific embodiment or embodiments disclosed or to the exact details

of construction shown, as obvious modifications will occur to persons skilled in the art.

Having thus described this invention, what is claimed and desired to be secured by Letters Patent is:

1. A latch comprising a bolt supporting bracket and a latch bolt slidably mounted therein, said bracket having a base to be secured to a support and a pair of ears extending forwardly from said base having aligned apertures in which the bolt slides and may swing about the axis of the bolt, said bolt having a loop handle portion swingable and slidable with the bolt, the sides of which straddle one of said ears and one of the sides of which is straddled by said ears, said bracket being provided with abutment means located in the path of sliding movement of said straddled side of the loop in one position of the swingable loop and located out of the path of sliding movement of said straddled side in another position of the swingable loop, said latch bolt being formed of a continuous rod having a continuous straight portion extending through said ears to form the bolt, the loop portion being continuous with said straight portion, the end portion of the loop extending to a position adjacent said abutment means so as to be engageable therewith.

2. A latch comprising a bolt supporting bracket and a latch bolt slidably mounted therein, said bracket having a base to be secured to a support and a pair of ears extending forwardly from said base having aligned apertures in which the bolt slides and may swing about the axis of the bolt, said bolt having a loop handle portion swingable and slidable with the bolt, the sides of which straddle one of said ears and one of the sides of which is straddled by said ears, said bracket being provided with abutment means located in the path of sliding movement of said straddled side of the loop in one position of the swingable loop and located out of the path of sliding movement of said straddled side in another position of the swingable loop, said abutment means straddling the bolt, said latch bolt being formed of a continuous rod having a continuous straight portion extending through said ears to form the bolt, the loop portion being continuous with said straight portion, the end portion of the loop extending to a position adjacent said abutment means so as to be engageable therewith.

3. A latch comprising a bolt supporting bracket and a latch bolt slidably mounted therein, said bracket having a base to be secured to a support and a pair of ears extending forwardly from said base having aligned apertures in which the bolt slides and may swing about the axis of the bolt, said bolt having a loop handle portion swingable and slidable with the bolt the sides of which straddle one of said ears and one of the sides of which is straddled by said ears, said bracket being provided with abutment means located in the path of sliding movement of said straddled side of the loop in one position of the swingable loop and located out of the path of sliding movement of said straddled side in another position of the swingable loop, said straddled side being movable from one side to the other of said abutment means, said latch bolt being formed of a continuous rod having a continuous straight portion extending through said ears to form the bolt, the loop portion being continuous with said straight portion, the end portion of the loop extending to a position adjacent said abutment means so as to be engageable therewith.

4. A latch comprising a bolt supporting bracket and a latch bolt slidably mounted therein, said bracket having a base to be secured to a support and a pair of ears extending forwardly from said base having aligned apertures in which the bolt slides and may swing about the axis of the bolt, said bolt having a loop handle portion swingable and slidable with the bolt the sides of which straddle one of said ears and one of the sides of which is straddled by said ears, said bracket being provided with abutment means located in the path of sliding movement of said straddled side of the loop in one position of the swingable loop and located out of the path of sliding movement of said straddled side in another position of the swingable loop, said abutment means straddling the bolt, said straddled side being movable from one side to the other of said abutment means, said latch bolt being formed of a continuous rod having a continuous straight portion extending through said ears to form the bolt, the loop portion being continuous with said straight portion, the end portion of the loop extending to a position adjacent said abutment means so as to be engageable therewith.
